A. B. SMITH

TELEPHONE TRANSMITTER

Filed May 7, 1923

FIG. 1

Fig: 2

— Inventor —
Arthur Bessey Smith

Chas. H. Candy. ATT:

UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS.

TELEPHONE TRANSMITTER.

Application filed May 7, 1923. Serial No. 637,169.

To all whom it may concern:

Be it known that I, ARTHUR BESSEY SMITH, a citizen of the United States of America, and a resident of Evanston, Cook County, and State of Illinois, have invented certain new and useful Improvements in Telephone Transmitters, of which the following is a specification.

My invention relates in general to telephone transmitters, but more in particular to transmitters in which the microphone element is of the granular carbon type, and the object of the invention is to provide a microphone which is well adapted for operation on relatively low current values and which has a comparatively high resistance.

Broadly stated, the desired object is accomplished by interposing a thin diaphragm of mica or other insulating material between the two electrodes of the microphone. The diaphragm has a number of openings through which free communication is maintained between the chambers on opposite sides thereof so far as contact and passage of the granulates is concerned, but which are small enough, nevertheless, to sensibly restrict the effective cross section of the granular mass. In addition, the openings are so disposed as to appreciably lengthen the current path between the electrodes. Thus the increased resistance is secured, in two ways, by decreasing the cross section and by increasing the length of the conducting path through the granular carbon.

The precise manner in which the invention is carried out will be described fully hereinafter, reference being had to the accompanying drawing, in which Fig. 1 is a cross section through a well known type of transmitter embodying the invention, while Fig. 2 shows the diaphragm hereinbefore referred to as being interposed between the electrodes.

Except for the microphone element, the transmitter may be of any well known design. As illustrated in the drawing it comprises a mouth piece 1; face plate 2 having an opening in which the mouth piece is held by screw threads; a heavy flanged ring 3, screwed into the rearwardly extending rim of the face plate as shown; a bridge 4, which is formed integrally with the ring 3; and a microphone cell supported in the

usual position on the bridge. There is also a main diaphragm 5 for receiving the air vibrations, and two terminals 6 and 7 by means of which the transmitter is connected in circuit.

The microphone consists essentially of the cup 8, front and rear electrodes 17 and 11, the granular mass of carbon occupying the space between the electrodes, and the perforated mica diaphragm or partition 20 which partially separates the carbon granules into two groups. The cup 8 is preferably of hard rubber, bakelite, or other suitable insulating material, and on the inside is cylindrical in shape for the greater part of its depth, there being, however, a conical depression at the bottom of the cup which terminates in a countersunk opening. The stem 9 passes through this opening and a corresponding bushed hole in bridge 4, and a nut 10 is employed to clamp the cup to the bridge. The rear electrode 11 is of carbon electroplated on one side and is soldered to the rear end of the stem 9. Its exposed surface is polished and is flush with the bottom of the conical depression in the cup. The partition 20, shown most clearly in Fig. 2, is preferably of mica, perforated as shown, and rests at the bottom of the cylindrical portion of the cup. To the left of the partition 20 is a brass ring 19, whose outer edge is flush with the edge of the cup. The front electrode 17 is attached to the head of stem 12 in the same manner as electrode 11 is attached to stem 9, and is slightly larger in diameter than the latter electrode. Diaphragm 21, of mica also, and used for sealing the end of the cup, is perforated in the center to permit it to be slipped in place over stem 12 where it is secured by washer 16 and nut 15. The diaphragm 21 is clamped against the brass ring 19 by means of the threaded cap 18, which also serves, therefore, to securely hold the said ring and the partition 20 in place. Stem 12 is secured to the main diaphragm 5 by means of nuts 13 and 14.

The granular carbon is of course introduced before the cup is sealed by clamping diaphragm 21 in place, and should be sufficient in quantity to nearly fill the cup. Carbon of the standard fineness may be used as in ordinary microphones, the openings in

the partition 20 being much larger than the individual grains in the standard grade of carbon, so that free circulation is maintained at all times.

5 In operation, the current cannot pass directly from one electrode to the other, owing to the partition, but must flow outwardly from one electrode toward the outside of the mass of carbon in order to pass through the

10 several openings and reach the other electrode. It will be understood therefore that the conducting path through the granulated carbon is somewhat longer than it is in the ordinary microphone without the partition,

15 in which the current can pass directly from one electrode to the other. It will be noticed also that the partition reduces to a considerable extent the effective cross section of the conducting mass of carbon; that is, instead of being approximately equal to the

20 actual cross section, the effective cross section is approximately equal to the sum of the areas of the several openings in the partition, which is a smaller value.

25 It will be evident from the foregoing that the relative size of the parts, and in particular the size and position of the openings in the partition, is of great importance in securing the desired results, and that by 20 suitably varying one or more of the essential dimensions any resistance desired may be obtained within a considerable range. The following table gives the principal dimensions in a working transmitter embody-

ing the invention which gave excellent results: 35

	Millimeters.
Diameter of rear electrode	6
Diameter of front electrode	8
Distance between electrodes	2.1
Number of openings in partition	6
Diameter of openings in partition	2.5
Diameter of circle enclosing openings	11.2

40 The transmitter referred to above had a resistance of approximately 400 ohms working on a current of .030 amperes.

Having described my invention what I consider to be new and desire to have protected by Letters Patent will be pointed out in the appended claim. 45

50 What I claim is:

55 A microphone comprising two electrodes with oppositely disposed parallel faces, comminuted resistance material occupying the space between said electrodes, an auxiliary diaphragm parallel to and midway between said electrodes, said diaphragm having a centrally located insulated portion equal in size to one of said electrodes, and a plurality of openings outside of said insulated portion, said auxiliary diaphragm reducing the effective cross section area of the comminuted resistance material and also increasing the length of the current path through it. 60

65 In witness whereof, I hereunto subscribe my name this 4th day of May, A. D., 1923.

ARTHUR BESSEY SMITH.
